MANUFACTURE OF PRESTRESSED CONCRETE SLEEPERS AND LIKE BEAMS

Ronald Samuel Vernon Barber and Dudley Roger Lester, Malvern, England, assignors to Dowsett Engineering Construction Limited, Malvern, England, a British company

Application December 4, 1944, Serial No. 566,600
In Great Britain September 28, 1943

2 Claims. (Cl. 254—67)

1

This invention consists of improvements in the manufacture of pre-stressed reinforced concrete sleepers and like beams and deals particularly with the means for applying tension to reinforcing wires before a casting operation and for relieving the external tension on said wires when the cast concrete has set and hardened.

In this specification the expression "sleepers" is used to include railway sleepers and similar beams. In the manufacture of pre-stressed reinforced concrete sleepers it is customary to employ mass production methods: thus long production lines are arranged to accommodate a large number of sleeper moulds in series. The first step is to arrange the reinforcing wires in the production lines and to apply tension thereto. The distribution of reinforcing wires over the cross-section of the sleeper is a matter of choice or design but one known scheme is to use the wires in pairs and to employ a number of such pairs (say 7 to 12 pairs). Normally there is at each end of each production line a sturdy pedestal embodying a perforated upright plate through which the wires are threaded. At one end of each production line the ends of the wires may be made fast while at the other end means are provided for applying and relieving tension.

In one method at present in commercial use the wires at the tensioning end are threaded through a sturdy pedestal and also through an anchorage plate which is capable of sliding longitudinally in fixed guides.

The tensioning of the reinforcing wires in this known method is carried out in two stages. In the first stage, each wire or pair of wires is given a preliminary tension and is secured to the anchorage plate, say by the action of wedges. For the second stage, hydraulic rams are introduced between the pedestal and the anchorage plate and oil under pressure pumped into the hydraulic rams so as to force back the anchorage plate to apply the final tension to the reinforcing wires, and distance pieces, such as stout metal rods, are secured between the pedestal and the anchorage plate to keep the wires in tension, the hydraulic rams being then removed for use at another production line.

The moulds are applied around the reinforcing wires, concrete is introduced into the moulds and a single production line may have a great many moulds in series. When the concrete has set and hardened, the reinforcing wires within each sleeper remain in tension but it becomes necessary to relieve the external tension on the wires. To enable the distance pieces to be re-

2

moved it has been necessary to replace the hydraulic rams and to force the anchorage plate backwards through a short distance, thus increasing the tension in the wires and this is very undesirable when the concrete has already set and hardened in the moulds. This known method of applying and relieving tension is subject to a number of disadvantages in addition to the one just mentioned. For example, the application of the tension through an anchorage plate operated by hydraulic rams may give rise to unequal stresses on the anchorage plate especially if the preliminary tensions on the wires have been unequal. Again it will be seen with the above arrangement where the anchorage plate moves along fixed guides there is a grave danger of slight tilting of the anchorage plate unless the guides therefor are of a very heavy construction. Further the operation of tensioning in two stages makes the process slow and uneconomical.

The object of the present invention is to overcome the above difficulties both when applying and when relieving tension in the reinforcing wires; and an incidental object is to facilitate the application to the different wires of different tensions according to the requirements of the designer.

According to this invention the tension is applied to the reinforcing wires in one stage. If the wires are used singly, i. e. separated from one another, the desired tension may be applied to one wire at a time. If according to the usual custom the wires are used in contiguous pairs, the desired tension may be applied to each pair, one pair at a time.

It is a feature of this invention that in any particular arrangement of reinforcing wires, the tension in certain wires may be greater than in other wires.

According to this invention at the tensioning end of the production line there is a stout fixed pedestal or permanent structure through which the reinforcing wires are passed. At the appropriate height for the reinforcing wires and at the back of the pedestal there is fixed a head also of sturdy construction and conveniently consisting of a number (say 8) of short sections of rolled steel joists. This head carries one or more horizontally-extending strong brackets which provide horizontal guides for the wire anchorage plate which can slide on said bracket or brackets and is separated from the head by several (say 3 or 4) stout adjusting screws. Each wire anchorage plate is provided with orifices through which reinforcing wires (generally in pairs) are

threaded. As above stated each wire (or preferably each pair of wires) receives only one tensioning operation. This tensioning operation is carried out at the back of the wire anchorage plate and is effected by known means, e. g. by hydraulic action, by screw action, by a winch or the like. The tension attained can be measured by an extensometer or other standard tension-measuring device. When the required tension has been attained the wire (or generally pair of wires) is fixed in the wire-anchorage plate by a wire-anchorage ferrule, by a simple wedge, by a screw-action wedge or by other wire-fixing device.

To prevent any tendency towards tilting of the wire-anchorage plate during the tightening operation, means may be provided for applying the tension to wires symmetrically on both sides of the vertical median line of the wire-anchorage plate. It will be understood that while the tension is being applied and while it is being maintained, the screws which secure the wire-anchorage plate in relation to the head are not moved or adjusted; in other words the pedestal, head and wire-anchorage plate are rigid.

After the casting operation is completed and the concrete has set and hardened, the method of releasing the external tension on the wires is to turn the adjusting screws so as to allow the wire-anchorage plate to approach the head from which it is carried. By this means the release of external tension of the wires is allowed to take place gradually and uniformly and there is no necessity to apply any further or additional tension to the wires.

When tension of the wires has been relieved to a sufficient extent, the wires can be released from the wire-anchorage plate by removal of the ferrules, wedges or like securing devices.

It will be understood that the method described for releasing the external tension on the reinforcing wires of one production line involves a movement of the wire-anchorage plate towards the head from which it is carried and therefore at the stage when the tension is applied to the wires, the anchorage plate must be withdrawn to the requisite extent by the action of the adjusting screws.

In the accompanying drawings which illustrate an example of this invention:

Figure 1 is a front elevation,

Figure 2 is a side elevation,

Fig. 3 is a plan, showing the head, pedestal and tensioning means, other parts being omitted,

Figure 4 is a section on an enlarged scale through one of the holes in the anchorage plate showing the disposition of a pair of wires and the wedge which secures them, and

Figure 5 is a diagram of the production lines.

The pedestal is formed by the upright rolled steel joists 12 joined by horizontal joists 13. The head comprises eight short upright sections 14 of rolled steel joists secured to the horizontal joists 13. A stout horizontal bracket 15 is secured to each pair of upright sections 14 and on this bracket 15 (which has guiding fillets 16) there slides a wire-anchorage plate 17 which is separated from the head by three stout adjusting screws 18. The horizontally spaced lower adjusting screws 18 bear against upright sections 14 and the upper screw 18 bears against filler block 14a which rests against upper joist 13. Between each two adjacent upright sections 14 is secured a horizontally extending rolled section

14a, the uppermost screw 18 of each plate 17 bearing against the associated section 14a.

Each hole 19 through the anchorage plate 17 conveniently accommodates a pair of wires 20 and one method of securing a pair of wires in the anchorage plate 17 is to force a wedge 21 between the wires and into the hole.

Separate means may be provided for supplying and guiding the reinforcing wires to the wire-anchorage plate, and when a complete group of wires has been threaded through the holes in the anchorage plate, that group of wires is pulled along the production line by a haulage rope where it is threaded through the head and the anchorage plate at the other end of the production line. To accommodate the haulage rope a hole 22 is provided in the anchorage plate 17.

Referring to Figure 4, it will be seen that when a pair of wires has been subjected to tension a wedge 21 (which may have grooves) is inserted into the hole 19 and between the wires 20 so as to secure the wires in their tensioned position.

In the drawings the wire-anchorage plates 17 are shown in an intermediate position of their possible travel but it will be understood that at the time when the tension is applied to the wires, the wire-anchorage plates (by means of the screw adjustment) are withdrawn some distance from the head 14 so that after the concrete in the moulds has set and hardened and the external tension on the wires has to be relieved, there is ample room for the movement of the wire-anchorage plate towards the head.

Referring to Figure 5, moulds 25 are arranged in long straight series and the reinforcing wires 26 pass through the moulds and through the end plates thereof so that when a mould has been filled with concrete the reinforced wires are embedded in the concrete in the mould. In Figure 5 the devices of this invention, viz., the joists 12, 13, 14, the brackets 15, the wire-anchorage plate 17 and adjusting screws 18 are shown only on the right-hand side of the drawing, but it will be understood that there is a similar arrangement at the opposite end of the production lines.

Beyond the production lines (i. e., outside the pedestals) there are transverse rails 27 on which a wire-tensioning truck 28 can be moved so that the tensioning device thereon (e. g., a fluid-operated ram) can be brought into line with any production line and the truck 28 can then be clamped to the rails 27.

It will be appreciated that when the trough-shaped moulds 25 are arranged in series in a production line, and when means for supporting the reinforcing wires 26 are provided as described, these reinforcing wires are secured at one end (say the right-hand end), then tension is applied to the wires (say by means of the wire-tensioning device 28) and then the wire-anchorage devices (not shown) at the tensioning end and are used to secure the wires under tension, but when the concrete in one line of moulds has set and hardened and when the time arrives for relieving the external tension in the wires 26, the adjusting screws 18 are unscrewed (at either end of the line).

We claim:

1. Apparatus for the manufacture of prestressed reinforced concrete sleepers comprising mechanism for maintaining under tension for a desired period of time, and thereafter releasing, an intermediate section of each of a plurality of elongated parallel wires which pass through a plurality of aligned concrete moulds and which

wires have been initially placed under tension by other means, said mechanism comprising opposed horizontally spaced wire gripping, holding and releasing devices, one such device including an immovable supporting part or standard having a surface disposed substantially in a vertical plane transverse to the direction in which the wires extend and a substantially horizontally disposed plate supporting surface, a stout wire anchorage plate slidably resting upon the plate supporting surface of said standard, said plate being disposed substantially parallel to the vertical surface of the supporting standard and having a series of horizontally extending apertures therein through which the parallel wires under tension pass, a releasable wire securing element extending into each such aperture, for laterally gripping and holding against movement relatively to said plate the wire passing through said aperture, and a plurality of screws operatively engaging the plate and the vertical face of the standard, said screws being adapted to maintain said plate and standard in spaced relationship, and the wires under tension, or to be actuated to permit the plate to move relatively to the rigid part, under

10

the pull of the wires, until the tension in the wires has been fully relieved.

2. The combination set forth in claim 1 in which three screws are provided, said screws being disposed substantially at the apices of a triangle within which the wire receiving apertures are located.
